UNITED STATES PATENT OFFICE.

THOMAS SHIPLEY, OF YORK, PENNSYLVANIA.

SUPPORTING AND INCLOSING MEANS FOR THE DRIVING-SHAFTS OF AMMONIA-COMPRESSORS.

1,250,037.

Specification of Letters Patent. Patented Dec. 11, 1917.

Application filed May 28, 1917. Serial No. 171,429.

To all whom it may concern:

Be it known that I, THOMAS SHIPLEY, a citizen of the United States, residing in the city of York, in the county of York and State of Pennsylvania, have invented a new and useful Improvement in Supporting and Inclosing Means for the Driving-Shafts of Ammonia-Compressors, of which the following is a specification.

My invention relates to ammonia compressors for use in ice and refrigerating machinery, and more particularly to compressors of the "inclosed type" so called—that is to say a compressor in which the compressor cylinders are erected upon a base known as the crank case which constitutes a chamber for reception of the crank shaft and its connections by which the compressor cylinder pistons are driven, the ends 20 of the compressor cylinders which rest upon the crank case being open and in free communication with the interior of said case, thus permitting a direct connection of the crank shaft with the cylinder pistons. In order to prevent the suction gas, which is liable to leak downward in small quantities around the pistons into the crank case below, from escaping therefrom into the surrounding air, as well as to prevent the oil used in the oiling system of the compressor, and usually contained in the base of the crank case as a reservoir, from splashing out therefrom, it is necessary to close all openings in the crank case tightly and securely to prevent the escape of the ammonia fumes as well as to maintain a proper pressure in the crank case, particularly when the oiling system involves the forced circulation of the oil through a pipe line under pressure, in a closed circuit completed through the crank case as described by me in another application for Letters Patent now pending in the U. S. Patent Office. My invention has to do with the closure for that opening in the crank case through which the crank shaft passes out from the case, and it consists in an improved combination and arrangement of instrumentalities for effectively maintaining a tight joint at that point notwithstanding changes in the alinement of the shaft due to the wearing down of the bearings or to other causes, which can best be explained in connection with the accompanying drawings forming part of this specification to which I shall

now refer for a better understanding of my invention.

In the drawings—

Figure 1 is a longitudinal vertical central section of so much of an ammonia compressor embodying my improvement in its preferred form as needed for the purposes of explanation—the section being in the vertical plane of the axes of the crank shaft and the compressor cylinders, the crank shaft and some of the other parts being in elevation.

Fig. 2 is a transverse vertical section of the crank case taken near the end of the same out through which the crank shaft passes. In this figure the view is of the crank case alone with the compressor cylinders and crank shaft removed. The crank case is in section so as to expose the adjoining crank shaft bearing which, together with its seat or supporting base, is in elevation.

In the drawings—

A is the crank case with side and end openings all of which, except that which is at the end of the case out through which the crank shaft extends, are closed by solid imperforate covers *a*, between which and the crank case gaskets *b* of suitable soft material are introduced as packing for the joint between them. B are the compressor cylinders erected on the crank case, and communicating at their open lower ends with the interior of the same. C is the crank shaft; D are the bearings for the same; E are the seats or supporting bases for the bearings; and F are the connecting rods between the pistons B' of the cylinders, and the cranks on the crank shaft.

The cover G for the opening at the end of the crank case out through which the crank shaft extends is, like the other covers *a*, tightly bolted to the crank case, and has a packing gasket *b* interposed between it and the annular border of the opening which it closes so as to make a gas tight joint therewith. The cover however, is not imperforate like the other covers, but is formed with a central circular opening *g* for the passage of the crank shaft, which opening, as shown, is concentric with the crank shaft, but of noticeably greater diameter than the shaft, so as to leave between the cover and the shaft quite a wide annular open space.

In this space is located a stuffing box H, 110

whose body h , which contains the packing, encircles the shaft, and whose outer flanged end or head h' overlaps, and fits closely against, the portion of the cover bordering 5 the opening, which portion serves as a seat against which the flange may be tightly held by screw studs h ; an annular follower l for compressing the packing encircles the shaft and is secured to the head of the stuffing box 10 by screw studs m , by means of which the follower can be caused to increase pressure upon the packing in the stuffing box as desired.

The body h of the stuffing box is of less diameter than the opening in the cover thus 15 leaving between the body of the stuffing box and the border of said opening an annular clearance or space n . The holes in the head h' of the stuffing box H , through which pass screw studs h by which it is secured to the 20 cover G , are of sufficiently greater diameter than the stems of the said studs to leave an annular clearance or space o around the stem of each stud which may be of the same width as the clearance space n around the stuffing 25 box, but at any rate is of a width to permit all needed crosswise movement of adjustment of the stuffing box within the limits of that space. Under this arrangement it will be seen that the stuffing box can readily be 30 adjusted and re-adjusted to conform to changes which may from time to time occur

in the alinement of the crank shaft and to the wearing down of the shaft bearings by continued frictional contact with the shaft, or to other causes, thus efficiently preserving 35 a close joint between it and the shaft, without disturbing the cover or the shaft bearings.

Having described my improvement what I claim herein as new and desire to secure by 40 Letters Patent is:

In an ammonia compressor of the inclosed type, the combination substantially as herein before set forth of the crank shaft and bearings therefor; the crank case in which the 45 same are housed; a cover for the open end of the crank case through which the crank shaft extends having a circular opening for the passage of said shaft of greater diameter than the shaft leaving an annular clearance 50 or open space between the shaft and cover; a stuffing box encircling the shaft and provided with a head which overlaps the portion of the cover that borders the opening therein, and is adjustable crosswise of said 55 opening, to conform the stuffing box to changes in alinement of the shaft; and means for tightly securing the stuffing box to the cover in its adjusted position.

In testimony whereof I hereto affix my signature.

THOMAS SHIPLEY.
